UNITED STATES PATENT OFFICE.

ARTHUR O. TABOR, OF WATERLOO, IOWA, ASSIGNOR TO WATERLOO AUTOMATIC STONE MACHINE COMPANY, OF WATERLOO, IOWA, A CORPORATION.

FENCE-POST.

SPECIFICATION forming part of Letters Patent No. 783,598, dated February 28, 1905.

Application filed March 12, 1904. Serial No. 197,738.

To all whom it may concern:

Be it known that I, ARTHUR O. TABOR, a citizen of the United States, residing at Waterloo, county of Blackhawk, State of Iowa, have invented certain new and useful Improvements in Fence-Posts, of which I do declare the following to be a full, clear, and exact description, reference being had to the accompanying drawings, forming part of this specification.

10 The present invention has relation more particularly to the class of fence-posts in which the body of the post is formed of concrete, artificial stone, or like plastic material strengthened by a metallic core extending lengthwise 15 of the post and embedded therein in the molding process.

10 The object of the invention is, first, to provide an improved construction of post, and, second, to provide improved means whereby 20 the fence-wires may be connected to the post. These objects of the invention are accomplished by the features of improvement hereinafter described, illustrated in the accompanying drawings, and particularly pointed 25 out in the claims at the end of this specification.

Figure 1 is a view in front elevation of a fence-post embodying my invention, the lower part of the post being shown as embedded in the earth. Fig. 2 is an enlarged view, in vertical section on line 22 of Fig. 4, through a portion of my improved fence-post and means for connecting the fence-wires thereto. Fig. 3 is a view similar to Fig. 2, but being in vertical section on line 3 3 of Fig. 4. Fig. 4 is a view 30 in cross-section on line 4 4 of Fig. 2. Fig. 5 is an enlarged detail front view showing a portion of the post and the fastener-plate in position thereon.

40 The body A of the post is formed of concrete or artificial stone and is preferably tapered somewhat from bottom to top, the corners of the post being preferably rounded. Embedded in the body A of the post in the process of molding the same are the metal 45 core-plates B and C, these plates extending from approximately the top to the bottom of the post. The core-plates B and C are arranged at right angles to each other, as by this means a far greater strength can be given

to the post, and each of the core-plates is 50 formed from a strip or sheet of perforated metal, the perforations of the metal being of sufficient size to permit the concrete or like plastic material of which the body of the post is formed to pass through the plates. The 55 plates B and C are preferably formed with oblong perforations b and c; but manifestly the size, shape, and arrangement of these perforations or cut-away spaces of the plates may be varied, as desired, without departing 60 from the spirit of my invention. By reference to Figs. 2 and 3 of the drawings it will be seen how the concrete or plastic material of which the post is formed fills the perforations of the plates B and C, thereby most 65 effectively retaining the plates in position. Inasmuch as the plates B and C extend at right angles to each other, they will manifestly impart a very great strength to the post in all directions.

70 From the plate B extends forwardly a series of fasteners designed to hold in position upon the post a fastening-plate whereby the fence-wires will be sustained. Preferably these fasteners consist of staples D, that pass 75 through perforations of the plate B and through the front face of the post, these staples D being embedded in the plastic material of the body of the post during the molding operation. The fastening-plate E is 80 formed with suitable openings through which the free ends of the staples D will be passed and is formed also with metal lips arranged at suitable distances throughout its length and adapted to engage the wires F, of which the 85 fence will be formed. Manifestly the post may be used for supporting any suitable style of fence, such as plain or barbed wires, wire-netting, or the like; but for convenience I have shown the post as supporting a fence 90 formed of simple wire strands. The fastener-plate E will have the retaining-lips e formed in any desired number throughout its length, and preferably these lips e are formed integral with the body of the plate E at the same 95 time that the holes or slots e' are formed in the body of the plate.

When a fence is to be set or strung upon

the post, each fastener-plate E will be set against the front of the post, the ends of the staples D at such time projecting through the slots or openings e' of the plate E and the fence-wires F extending between the fastener E and the lips e, that extend inwardly therefrom. The free ends d of the staples D will then be bent outwardly, as shown in the drawings, so as to retain the fastener-plate E in position, and the lips e of the fastener-plate will then be bent outwardly around the wires F and clenched on the outside. At the upper part of Fig. 2 of the drawings one of the lips e is shown in extended position before being clenched about the uppermost wire F; but the (remaining) wires shown in Fig. 2 have the lips e bent and clenched around them. The wires F may extend either above or below the staples D, as indicated in the drawings. It will be understood, of course, that such intermediate lips e as are not used will remain inside, as indicated in Fig. 2 of the drawings.

I wish it understood that the details of construction above set forth may be varied without departure from the spirit of my invention and that features of the invention may be employed without its adoption as an entirety.

Having thus described my invention, what I claim as new, and desire to secure by Letters Patent, is—

1. A fence-post formed of plastic material having embedded therein separate perforated metal core-plates extending longitudinally of the post, both of said core-plates being completely surrounded by the plastic material, one of said core-plates extending at right angles to the front face of the post in substantially central position and the other of said core-plates being arranged adjacent the back face of the post and extending at right angles to the other of said core-plates.

2. A fence-post formed of plastic material and having completely embedded therein longitudinal core-plates arranged at right angles to each other, one of said core-plates being arranged behind and at right angles to the front face of the post and being provided with fasteners extending through said core-plate

and projecting through the plastic material covering the front edge of said core-plate and through the front face of the post.

3. A fence-post formed of plastic material and having completely embedded therein a longitudinal core-plate extending at right angles to the front face of the post, staples passing through said core-plate and projecting beyond the front face of the post and a perforated retaining-plate through which said staples will pass when the fence is in position upon the post.

4. A fence-post formed of plastic material having embedded therein a perforated longitudinal core-plate, the body of the plastic material extending through and completely surrounding the front, sides and back of said core-plate, and staples extending through the holes of the core-plate and projecting through the plastic material and beyond the front face of the post.

5. A fence-post formed of plastic material provided with a core, fasteners extending from the core through the front face of the post and a fastener-plate provided with lugs extending inwardly whereby the fence-wires may be held between the fastener-plate and the post.

6. The combination with a fence-post having fasteners projecting from its front, of a fastener-plate perforated to receive said fasteners and provided with a plurality of lugs formed integral therewith and extending inwardly and upwardly at the back of the plate and adapted to be clenched about the fence-wires.

7. A fence-post formed of plastic material having embedded therein a metal core and having a plurality of U-shape fasteners projecting beyond its front face, in combination with a fastener-plate perforated to receive said U-shape fasteners and provided with lugs to engage the fence-wires, the outer ends of said U-shape fasteners being clenched over said fastener-plate.

ARTHUR O. TABOR.
